[57] CLAIM

The ornamental design for a chest of drawers, as shown and described.

DESCRIPTION

FIG. 1 is a top perspective view of a chest of drawers showing my new design;

FIG. 2 is a top plan view thereof;

FIG. 3 is a front elevation view thereof;

FIG. 4 is a side elevation view, the opposite side being a mirror image thereof;

FIG. 5 is a top perspective view of a chest of drawers showing a second embodiment of my new design;

FIG. 6 is a top plan view thereof;

FIG. 7 is a front elevation view thereof;

FIG. 8 is a side elevation view thereof, the opposite side being a mirror image thereof;

FIG. 9 is an enlarged fragmentary sectional view taken along line 9—9 of FIG. 3;

FIG. 10 is an enlarged fragmentary sectional view taken along line 10—10 of FIG. 3; and,

FIG. 11 is an enlarged fragmentary sectional view taken along line 11—11 of FIG. 3.

The rear and bottom of the chest of drawers form no part of the claimed design.
